UNITED STATES PATENT OFFICE.

JOSEPH FERGUSON, OF PHILADELPHIA, PENNSYLVANIA, ASSIGNOR TO
STEAD & MILLER, OF SAME PLACE.

DESIGN FOR CHENILLE FABRIC.

SPECIFICATION forming part of Design No. 15,189, dated August 5, 1884.

Application filed May 13, 1884. Term of patent 3½ years.

To all whom it may concern:

Be it known that I, JOSEPH FERGUSON, a citizen of the United States, residing at Philadelphia, in the county of Philadelphia and State of Pennsylvania, have invented and produced a new and original Design for a Pattern to be Inwrought in Chenille Fabric.

Said pattern consists of an ornamental dado of flowers, stems, and leaves, guards of plain 10 and ornamental cross-stripes, and a cross-border of flowers, stems, and leaves, as is illustrated by the accompanying photographic print; and I do hereby declare that the photographic print accompanying this specification conveys to any

one skilled in the art of weaving chenille fabrics a clear understanding of the same, and is sufficient to enable such persons to use my invention. 15

What I claim as my invention, and desire to secure by Letters Patent, is— 20

The design for a chenille fabric, as shown in the photographic print accompanying this specification.

JOSEPH FERGUSON.
